UNITED STATES PATENT OFFICE.

ALBERT WINTON, OF FREDERICK COUNTY, MARYLAND.

IMPROVEMENT IN WATER-WHEELS.

Specification forming part of Letters Patent No. 37,539, dated January 27, 1863.

To all whom it may concern:

Be it known that I, ALBERT WINTON, of the county of Frederick, in the State of Maryland, have invented and made certain new and useful Improvements in Water-Wheels; and I do hereby declare that the following is a full, clear, and exact description of the nature, construction, and operation of said improvements, reference being had to the accompanying drawings, making a part of this specification, in which—

Figure 1 is a vertical sectional view of the wheel. Fig. 2 is a sectional view through the diameter of the wheel. Fig. 3 is an inverted view of the bottom or under side of the wheel. Fig. 4 is a perspective view of the wheel with a fragment off the side or circumference, so as to show the form and arrangement of the buckets of the wheel. Fig. 5 is a top view of the wheel, the gate, and framing thereof.

The nature of my improvements relates more particularly to the form and arrangement of the buckets or floats of a turbine water-wheel, together with the peculiar construction of a circumferential or surrounding adjustable gate, and also of peculiarly arranged chutes or inlets through all of which, in combination, the volume of water is so applied as to greatly economize the quantity thereof, yet will bring about a greatly increased force or power in operating the wheel.

The better to enable others to be skilled in the construction and operation of my improvements, the following is a description thereof:

In Fig. 1, at *a a a a a a*, is represented the superstructure or support on which the wheel is affixed, both of which are to be submerged within the penstock or reservoir of the mill. At *b b b* is the tub part of the cast-metal wheel, formed with a central partition or diaphragm, *c c*, and hub *d d*. To the bell-shape sides *e e e* of the wheel, which also has a way-rim, *f f f f*, formed on its upper edge around it, are affixed the floats or buckets *g g g g g g*, twenty-two in number, (see sectional Fig. 1 and also Fig. 4,) their vertical sides being slightly curved, as at *h h h h*. Said buckets or floats continue downwardly about two-thirds the depth of the tub-rim *e e e e*, when they bend or curve upwardly in an arc of a quarter-circle, as at *i i i i*. Thence they continue downwardly at an angle of twenty-two

degrees, as at *j j j j*, and also incline outwardly from the side of the tub at an angle of about thirty-four degrees, as shown at *k k k k*, Figs. 1 and 4. These buckets or floats are arranged around the circumference of the tub *e e e e* at equal distances, and diverge outwardly from the center or axis of the hub *d d*, and from the true radius thereof at an angle of fourteen degrees, as indicated by the red lines *l l l l*, Fig. 2—that is to say, at the point of connection of the vertical part *h h h h*, said connection, instead of being in a true radial line outwardly from the center or axis point *m m* of the hub *d d*, is in an oblique line, starting from the right of the axis, as at *n n n n*, Fig. 2; but at the same time the outward edge, *o o o o*, of the buckets, when in position, are in a true radial line from the axis of the wheel. The buckets or floats *g g g h i j k* may be cast together with the rim or tub part of the wheel, or separately, and bolted onto the circumference of the tub. On the outer edges of the curved part of the buckets is attached a surrounding band or hoop, *p p p p*, of a slightly less diameter than the wheel, having an upper flange-rim or shoulder, *q q q q*, Figs. 1 and 4, on which, as a base or support, the buckets are affixed, the buckets having a portion of their outer lower edges cut out sufficiently to fit onto the hoop or band, as at *p p p p q q q q*, Figs. 1 and 4. Thus, having formed the wheel, it is to be fitted securely onto a suspending spindle or shaft, *r r r r*, with a larger end or butt, *s s*, Fig. 1. Combined with the wheel is a cap or disk-like covering *t t t t*, formed with a circular rabbit or shoulder, *u u u u*, so as to fit over the way-rim *f f f f*, Fig. 1. To this disk is affixed permanently a hollow column or supporting-sleeve, *v v v v*, having a collar-rim, *w w*, the bore of the column being sufficiently larger in diameter than the vertical shaft so as to admit of required play around the same. On the collar end of the column is arranged an adjustable step or easing-seat, *x x x x*, formed with a neck or tube part, *y y*, fitting around the shaft or spindle and within the collar part thereof, said neck or tube part having an annular or ring formation, *z z*, provided with adjusting-screws *a² a² a²*, Figs. 1 and 5. To the shaft *r r r* is fitted a circular collar, *b² b²*, having a tightening-screw, *c²*. By said devices of the step and circular collar the wheel

can be elevated more or less, and may be suspended so as to rotate horizontally. To the top surface of the disk or cap are three or more yoke-like standards or braces, $e^2 e^2 e^2$, which stride the rim $f^2 f^2$ of the circular gate $g^2 g^2$. This gate, which is formed of a drum-like shape or as a wide band, is of metal and surrounds the wheel and buckets, and is arranged in such a manner as to be adjustable up and down, so as to graduate the inflow of water in its passage to the wheel. To the lower edge of said gate are affixed series of horizontally-attached flange chute-guides $h^2 h^2 h^2 h^2 h^2$, Figs. 1 and 4. This circular gate can be elevated and depressed by any suitable lever or other mechanism, and moves up and down between the yoke-like standards or braces $e^2 e^2 e^2$. Attached securely by bolts or screws to the superstructure is a metallic way of annular shape, as at $i^2 i^2 i^2 i^2$, having a rabbet or shoulder formation, $j^2 j^2 j^2$, within which the flange or shoulder part $q q q q$ of the wheel moves or plays sufficiently free so as not to rub or bear thereagainst. At equal distances around this way $i^2 i^2 i^2 i^2$, toward the outer circumference thereof, are affixed, by bolts or otherwise, vertically-arranged chute-guides $k^2 k^2 k^2 k^2$, being thirty-two in number, or, as a general thing, averaging about one-third more in number than the buckets or floats of the wheel. These chute-guides are in relative position to the side of the wheel at about an angle of thirteen degrees obliquely from the circumference of the wheel, and nearly at right angles to the vertical buckets or floats, as seen in Figs. 1, 2, 4. Said guides, together with the flange chute-guides $h^2 h^2 h^2 h^2$, when combined and arranged in position, form sloping inlets or chute channels all around the circumference of the wheel, as at $l^2 l^2 l^2 l^2$, Figs. 1 and 4. If found necessary further to strengthen the chute-guides or stay them more firmly in position, an annular rim may be affixed around their upper extremities, so as to bind them and keep them in their upright position. Thus having formed the wheel and other necessary parts complete, the whole will be then ready for placing in position within the reservoir or penstock of the mill, the under part of the wheel being elevated above the ground work, so as to prevent any contact with obstructions, and to admit of the spent water passing freely out into the "tail-race" below.

The operation of my improvements is as follows—viz: When the wheel is to be put in motion, the adjustable circular gate $g^2 g^2 g^2 g^2$ is to be elevated as required (more or less) so as to open the chute-channels or inlets $l^2 l^2 l^2 l^2$, Figs. 1 and 4, so as to admit the required volume of water surrounding the wheel, when the inflow of the water, being divided into numerous small columns by the chute-guides $k^2 k^2 k^2 k^2$ with the flange-guides $h^2 h^2 h^2 h^2$, said channels having inwardly-sloping sides, causes the small columns of water to rush against the vertical surface of the buckets

with great force, and, owing to the curved side of the vertical part of the buckets or floats, the centrifugal force of the wheel is entirely counteracted, for the inflowing water, instead of being thrown off outwardly, is retained thereby and its whole energy or impulse brought into use, and whereby the direct hydraulic action is also applied. The volume of water after acting on the vertical surface of the buckets descends upon the lower concave and sloping surface of the buckets, where it is sufficiently long retained to afford a full reactive force, and then, having expended its inherent hydrostatic power and impulsive force, flows out through the vents or outlets beneath the wheel and passes off to the tail-race.

The design of employing an excess of chutes or inlets is to divide the descending column of water, so as to multiply the impact force. The area of the upper part of the bucket is full one-half more than the area of ingress through the chutes or inlets. By elevating or depressing the gate with its chute-guide attachments $h^2 h^2 h^2 h^2 h^2$, as hereinbefore mentioned, a greater or less inflow of water may be applied, and by this mode of applying the water-power the line of force of the small columns of water is obliquely thrown off from a direct motion toward the center of the wheel, and consequently the energy or force of the water will be acting on the periphery of the wheel, whereby greatly increased leverage is obtained, affording multiplied momentum to the wheel, the dead inward centrally-tending pressure being entirely counteracted.

The advantages claimed for my improvements are as follows—viz: In the use of the present most approved turbine-wheels, experience has shown that the full impulse of the volume of water applied thereto cannot be developed, because the volume of water acting against the buckets is greater in proportion than the surface or area of the bucket and therefore crowds or packs so against the buckets all around as to produce a counteraction; but by my mode of using the vertical chute-guides and the adjustable gate and guides the main volume of water is broken up or divided into series of smaller columns less than the space between each bucket, instead of admitting therein the full direct flow against the surface of the buckets, which would tend to clog or "drown" the wheel by overloading it. Thus preventing these difficulties by my construction of wheels, a multiplied energy or impact force is brought directly against the leverage of the buckets, the dead-pressure of the water is prevented and, instead, is converted into impulse, and the reactive power fully and economically developed.

Having fully set forth and described the nature, construction, and operation of my improvements, and desiring to secure the same by Letters Patent of the United States, what I claim as new and useful is as follows—viz:

1. The construction of a turbine water-

wheel, $b b b b e e e e$, formed with a close horizontal diaphragm or partition, $c c$, and hub d , the buckets or floats $g g g g$, whose outer vertical edge longitudinally is slightly curved, as at $h h h h$, said buckets or floats arranged or standing relative to the center or axis of the wheel at an angle of fourteen degrees, and whose lower part is the arc of a quarter-circle, as at $i i i$, and continuing sloping downwardly at an angle of twenty-two degrees, as at $j j j j$, and likewise inclining outwardly at an angle of about thirty-four degrees, as at $k k k$, Figs. 1 and 4, so that the inflow of water may be received from and in the direction substantially in the manner as set forth and described.

2. The cap-covering $t t t t$, formed with a circular rabbet or shoulder, $u u u u$, and the suspending-sleeve or hollow column $v v v v w w w w$, with the adjustable step or casing-collar $x y z a^2 a^2 a^2$, combined and arranged substantially as shown in Figs. 1 and 5, and as set forth.

3. The mode of suspending the wheel through means of the adjustable collar $b^2 b^2 b^2$

$b^2 c^2$, as shown in Figs. 1 and 5, and as set forth and described.

4. The construction of the peculiar surrounding adjustable gate $f^2 f^2 f^2 f^2 g^2 g^2 g^2 g^2$, formed with the chute-guides $h^2 h^2 h^2 h^2$, Figs. 1 and 4, substantially as set forth and described, and in combination with the wheel, as shown in Figs. 1 and 4.

5. The special arrangement of the vertical chute-guides $k^2 k^2 k^2 k^2$ at the angle of thirteen degrees, and when so arranged around the circumference of the wheel and buckets thereof as to divide the inflow of the main volume of surrounding water into numerous small columns one-third greater in number than the number of buckets, and whereby the said columns strike the surface of the buckets nearly or quite at right angles thereto, substantially as in the manner set forth and described.
